UNITED STATES PATENT OFFICE.

WATSON R. SMITH, OF JACKSON, MICHIGAN.

SPRING STRUCTURE.

1,399,030.

Specification of Letters Patent.

Patented Dec. 6, 1921.

Application filed March 1, 1921. Serial No. 448,791.

To all whom it may concern:

Be it known that I, WATSON R. SMITH, a citizen of the United States, residing at Jackson, in the county of Jackson and State of Michigan, have invented new and useful Improvements in Spring Structures, of which the following is a specification.

This invention relates to spring structures.

10 One object of the invention is to provide a spring structure embodying a base frame strip to which the facing or skirt of the upholstering material may be readily tacked or otherwise secured and to which base frame strip the spring supporting bars may be readily sprung or snapped into detachable connection.

Another object resides in the provision of a spring structure, embodying among other 20 characteristics, a base frame composed of sheet metal and provided with a wood insert to which the lower edge of the side facing or skirt of the upholstering material may be readily tacked and also provided with means 25 whereby the spring supporting bars may be formed to provide for an effective detachable connection between the spring supporting bars and the frame strip.

With these and other objects in view, the 30 invention consists in the construction and novel combination of parts hereinafter fully described, illustrated in the accompanying drawings and pointed out in the claims here-to appended, it being understood that various changes in the form, proportion, size and minor details of construction, within the 35 scope of the appended claims, may be resorted to without departing from the spirit of the invention or sacrificing any of the advantages thereof.

In the drawings:—

Figure 1 is a transverse sectional view through a spring structure illustrating one embodiment of the invention.

45 Fig. 2 is a detail fragmentary perspective view of this particular embodiment of the invention.

Fig. 3 is a transverse sectional view of a modified form of the invention.

50 Fig. 4 is a detail fragmentary perspective view of this second form of the invention.

Fig. 5 is a detail fragmentary perspective view of a third embodiment of the invention.

Referring to the accompanying drawings, 55 and more particularly to Figs. 1 and 2, the reference character 6 indicates a sheet metal

base frame provided with a horizontally outwardly opening groove 7 adapted to receive a wood insert 8 and to which the lower edge of the side facing 9 may be secured by 60 means of tacks or other suitable fastening elements 10. It will be understood that the wood insert extends entirely around the base frame and where the base frame corners are rounded, the wood insert may be properly 65 secured in place by a steaming or wetting process to which the wood insert may be subjected.

The base frame strip may have an inwardly opening comparatively shallow 70 groove 11 into which is adapted to be sprung or snapped a rib 12 carried by the hook 13 at each end of the spring supporting bars 14 upon which latter the springs 15 are mounted in any suitable manner, one way being to 75 provide the bars 14 with a raised rib 16 and strike up or otherwise provide therein the eyes 17 to receive the lower convolutions of the springs.

The hooks 13 of the bars 14 overhang 80 the upper edge of the base frame strip as shown and these hooks have a more or less snug connection with both sides of the upper portion of the base frame strip with the ribs 12 of the hooks fitting tightly in the in- 85 wardly opening groove 11. That portion of each hook beneath the rib 12 lies flat or flush against the inner face of the outwardly opening groove 7 so as to provide for a substantial support for the ends of the spring sup- 90 porting bars 14.

Referring to Figs. 3 and 4 of the accompanying drawings, there is a slightly different construction involved. For instance, the base frame strip 6' has the upper groove 18 opening outwardly for the reception of a rib 19 carried by the hooks 13', these hooks 13' overhanging the upper edge of the base frame strip, as in the first form of the invention, and constructed whereby the ribs 19 100 are adapted to spring into the outwardly opening grooves 18 in the same manner and for the same purpose as in the case of the ribs 12 of the hooks 13 with relation to the inwardly opening groove 11 in the first form 105 described.

In this second embodiment of the invention, the wood insert 8' is disposed rearwardly or inwardly of the body of the base frame strip rather than outwardly thereof 110 as shown in the first form described. The hooks 13' are therefore formed so as to pro-

vide a part 20 adapted to overlie the upper wall of the lower outwardly opening groove 7' which receives the wood insert 18 and having a downwardly directed part 21 5 adapted to lie against the rear wall of the groove 7' and thereby provide for a firm and substantial support of the spring supporting bars.

In Fig. 5 the base frame strip 7^a is provided with the outwardly opening groove to receive the wood insert 22 in a manner similar to the other forms described and this base frame strip also has an outwardly opening groove 23 adapted to receive the 15 rib 24 of the hooks 13^a. In this embodiment of the invention, the hooks are not formed as nearly U-shaped as in the other two forms of the invention described but on the other hand take a formation more 20 on the order of inverted V-shape, and the inner sides of the hooks 13^a extend from the upper edge of the base frame strip 7^a upon an incline downwardly over the upper rear corner of the wall of the groove which receives the wood insert 22 and downwardly 25 beyond the latter to a point substantially in alinement with the lower wall of the wood insert groove, as clearly shown in Fig. 5. The principle of operation with regard to 30 this last embodiment of the invention is the same as in the other forms of the invention, the hooks being snapped or sprung into engagement with the base frame strip.

What is claimed is:—

35 1. In a spring structure, a base frame provided with upper and lower grooves, a wood insert in the lower groove, and a supporting bar provided with a hook at each end, with each hook provided with a rib adapted

to spring into the upper groove of the base 40 frame strip.

2. In a spring structure, a base frame strip composed of sheet metal and provided with upper and lower grooves, a wood or fiber insert in the lower groove, a spring 45 supporting bar provided with a hook at each end adapted to overhang the upper edge of the base frame strip and provided with means adapted to be sprung into co-active relation with the upper groove of the 50 base frame strip, whereby to effect a detachable connection between the supporting bar and the base frame strip.

3. In a spring structure, a base frame composed of sheet metal and provided with 55 a groove, a wood insert in the groove, and a spring supporting bar provided with a hook, at each end adapted to overhang the upper edge of the base frame strip, the base frame strip and the hooks of said bar being provided with interlocking connections whereby to effect a snapping connection between 60 the same and permit of detachable relation.

4. In a spring structure, a base frame composed of sheet metal and provided with 65 a groove, a wood insert in the groove, and a spring supporting bar provided with a hook at each end for connection with the strip, the strip and the hooks of the bar being provided with interlocking connections whereby to effect a snapping connection between 70 the same and yet permit of detachable relation and also of an adjustment of the bar along the strip.

In testimony whereof I have hereunto 75 affixed my signature.

WATSON R. SMITH.
